UNITED STATES PATENT OFFICE

JOHN D. BALDWIN, JR., OF CLEVELAND, OHIO, ASSIGNOR TO ALBERT J. WEATHERHEAD, JR., OF CLEVELAND, OHIO

METHOD OF MAKING COCKS OR VALVES

Application filed May 3, 1928. Serial No. 274,705.

The present invention relates to a method of producing relatively small bodies of angular formation from solid rods or bar stock, particularly valves or cocks. Thus one object of the invention is to produce a valve body in a facile and inexpensive way by automatic machinery, using drawn or extruded brass rods or bars of special formation. As an exemplification of one form of article 10 which can be made in that way, see the accompanying drawings, in which Fig. 1 is a perspective view of a rabbeted rod which is partly round and partly rectangular, and from which a valve body may be readily produced. Fig. 2 is a sectional view and side elevation of the same rod with a valve body partly produced thereon. Figs. 3 and 4 are side and end views of the valve body shown in Fig. 1, but severed from the rod. Fig. 5 is a side 20 view of the valve body, and Figs. 6, 7, and 8, are sectional views thereof, illustrating four successive steps in the production thereof after it has been severed from the rod. Fig. 9 is a sectional view, on a larger scale, of the 25 valve body as it appears after the last or finishing step. Fig. 10, is a sectional view, of the finished valve body and a screw-valve member, assembled. Fig. 11 is a sectional view of a modified form of rod stock.

In practicing this method, a brass rod or bar A of a predetermined cross sectional shape is first produced or provided. This rod or bar may be of extruded stock, or stock formed into the desired cross sectional shape 35 by drawing, rolling or in any other suitable way. As an exemplification of two cross sectional forms of rod which may be used to produce an angular valve body B, simply and cheaply, reference may be had to Figs. 1 and 40 11 in the drawings. In Fig. 11 the rod is of key-hole shape in cross section, and in Fig. 1, the rod is of corresponding shape, that is, it is of reduced width or rabbeted lengthwise at 2-2 to provide a narrow flange, rib or extension 3 centrally of a larger body portion 4. In Fig. 11 the enlarged body portion is circular, but in Fig. 1 the body portion 4 is partly rounded and partly flat-sided. This cross sectional formation of rod A is of utility 45 as it avoids waste of material in producing

an angular valve body as hereinafter set forth.

Thus, rod A is introduced into and fed through a collet in an automatic screw machine, the enlarged body portion 4 of the rod being fed axially through the collet with the angular rib or rabbeted portion 3 off center in respect to said axis. The end portion of the rod is then turned down to two different diameters at two separated places to provide 55 a large cylindrical extension 5 and a smaller cylindrical extension 6 axially of the larger body portion 4 of the rod. The stock intermediate or between the two cylindrical portions 5 and 6 retains the contour or shape of the original rod, but while the rod is still held in this same automatic screw machine, the outer or larger cylindrical extension 5 is drilled substantially its full length and the outer corner edge of the drilled opening 8 is 60 chamfered. These operations being completed the larger extension 5 is threaded, preferably with a die, and the smaller cylindrical portion 6 is also threaded, preferably by rolling. These operations proceed while 65 the sections operated upon are still an integral part of the rod, and then this section is severed or cut off.

The next step involves the placing of the cut-off section or valve body B (see Fig. 3) 20 within the chuck or collet of a second automatic screw machine to permit operations to proceed on the squared or angular projection 3' which extends from the middle of body B at right angles to the cylindrical portions 5 and 6. Then the angular projection 3' is turned round (see Fig. 5) and at the same time drilled to different diameters, thereby providing an annular valve seat 9 at the intersection of a small bore 10 and a larger 25 counterbore or entrance 11, see Fig. 6. The round projection 3' is then threaded on the outside, and the counterbore 10 tapped, see Fig. 7. A round hole 12 is then drilled axially within the smaller cylindrical extension 6, see Fig. 8.

The next operation consists in placing the product of the aforementioned steps in a machine which drills two round communicating holes or passages 14 and 15 in body B be- 100

tween the inner ends of the drilled openings 8 and 12 and the opposite sides of bores 11 and 10, respectively. The holes 14 and 15 are drilled at an inclination relatively to the axes of end openings 8 and 12 so as to communicate with bores 11 and 10 above and below the valve seat 9. Preferably, the angle holes 14 and 15 are drilled in opposite directions simultaneously, but they can be drilled in a 10 drill press separately at increased production costs.

The valve body per se is now completed, and a valve member C having a screw-threaded stem 16 and a handle 17 may be screwed

15 into the screw-threaded bore 11, and a packing nut or cap 18 may be screw-connected with the external screw-threads on the side projection or extension 3', as delineated in Fig. 10, thereby completing the valve.

20 The steps taken to produce a finished valve body from solid rod stock are rapidly and accurately performed, and the cost of production of a shut-off cock or valve made in the way described is greatly reduced com-

25 pared with other methods and practices known to me, and furthermore, the product itself is exceptionally sturdy and satisfactory for the purposes intended, especially in the diminutive sizes which are used extensively

30 with copper pipes of small diameter, for example, with the relatively small air and gasoline feed pipes used generally in automobiles.

What I claim is:

35 1. A method of producing a valve body, which includes the steps of forming a reduced cylindrical portion off center in and lengthwise of a rod, and of severing from the main body of the rod a section thereof 40 adjacent to and including said cylindrical portion.

45 2. A method of producing a valve body from a rod or bar of varying width in cross section, which includes the formation of a reduced cylindrical portion longitudinally in the wider part of the bar, and the production from the narrower part of the bar of a cylindrical extension at right angles to the axis of said bar.

50 3. A method of producing an angular body from a rabbeted rod or bar, which includes the step of forming cylindrical portions at spaced intervals lengthwise of the bar in the main body of the bar, and of producing a cylindrical extension at right angles to said main body in the rabbeted portion of the bar intermediate said cylindrical portions.

55 4. A method of producing an angular body consisting in machining a section of a rod at spaced intervals lengthwise of its axis and eccentric thereto to a cylindrical form, in turning the unmachined portion of said severed part to a cylindrical form around an axis at right angles to the main axis of the 60 severed part, and in drilling separate open-

ings lengthwise of each cylindrical portion and into intersecting relation.

5. A method of producing a valve body, consisting in forming spaced cylindrical portions off center in a rod and leaving an angular projection between the cylindrical portions; in screw-threading both cylindrical portions while still integrally a part of the rod; in severing the treated section at its junction with the main body of the rod; in turning and screw-threading the angular projection; and in drilling communicating passages at different angles through said cylindrical portions and angular projection. 75

6. A method of producing a valve body, 80 consisting in placing a rod of irregular cross-sectional shape off-center in the collet of an automatic screw-machine, and forming spaced cylindrical portions and an intermediate angular portion coincidently in a section of said rod by a turning operation; in

85 rolling a screw-thread on the turned cylindrical portion before severing the treated section; in drilling one of said cylindrical portions; in severing the section at its juncture with the main body of the rod; in turning and screw-threading the angular portion; in drilling bores of different diameter axially of the turned angular portion and in the main body of the severed section; and then drilling 90 communicating passages through said cylindrical portions and the body. 95

7. A method of producing a valve body, which consists in forming spaced cylindrical portions and a right-angled extension in a 100 rod, of varying width in cross section, in screw-threading said cylindrical portions, in severing the formed section from the main body of the rod, in turning the said extension, in drilling a bore and forming a valve 105 seat axially of said extension, in screw-threading said bore and extension, and in drilling passages lengthwise of said cylindrical portions at an angle to the axis thereof to communicate with said bore on opposite 110 sides of said valve seat.

8. A method of producing a passaged body, from rod stock which is partly angular and partly round in cross section, consisting in making a section of the rounded portion of the rod cylindrical and leaving the angular portion extend at right angles to the axis of the cylindrical portion, in drilling said angularly related portions to provide angularly related communicating passages, and in screw-threading the cylindrical extension and the entrance to one of said passages. 115

9. A method of producing a relatively small valve body from solid rod stock which is partly round and enlarged and partly of 120 reduced angular and rabbeted formation, consisting in removing portions of the angular rabbeted portions at spaced intervals in the rod and coincidently forming spaced cylindrical portions in the enlarged part of the 125

rod, in severing the partially completed valve body from the rod, in turning the reduced rabbeted portion of the body cylindrical and drilling a transverse opening therein while 5 coincidently forming a valve seat centrally of the body, and in drilling openings through the spaced cylindrical portions at an inclination to the axes thereof and to communicate with said transverse opening in opposite sides 10 of said valve seat.

10. A method of producing a valve body from a solid rod of varying width in cross section, consisting in turning the rod to a cylindrical form at spaced intervals and leaving 15 an angular projection intermediate the cylindrical portion, in drilling one cylindrical part and rolling a screw-thread on the other cylindrical part and then severing the piece which has been operated upon from the main 20 body of the rod, and subsequently drilling the said piece to provide communicating passages and a valve seat.

11. In a method of producing an angular body from a solid rod of irregular contour 25 in cross section, the steps herein described of boring one end of a rod and forming reduced cylindrical portions at spaced intervals lengthwise of the rod parallel with the offset in respect to the main axis of the rod and 30 then severing the part so formed adjacent to one of said cylindrical portions, and subsequently forming a communicating passage in said part with said bore.

12. A method of producing a passaged 35 body from a revolving rod of irregular width in cross section, including the steps of forming reduced screw-threaded cylindrical portions co-incidently at spaced intervals in the rod while drilling an opening in one end 40 thereof, then severing from the main body of the rod the part operated upon, and finally in producing intersecting passages in said part.

13. A method of producing a passaged body 45 consisting in forming spaced cylindrical portions and a right-angled extension in a rod of varying width in cross section, in screw-threading said cylindrical portions, in drilling one screw-threaded part and then severing the piece which has been operated upon from 50 the main body of the rod, in drilling a transverse opening in said piece within the right-angled extension while co-incidently forming a valve seat centrally of the body, and in drilling openings through the spaced cylindrical portions at one side of the axis thereof in communication with said transverse 55 opening at opposite sides of said valve seat.

14. A method of producing a valve body, 60 which includes the steps of forming reduced cylindrical portions at spaced intervals lengthwise of a rod and offset to the main axis of the rod, and severing of equal sections including said cylindrical portions of the main body of said rod.

15. A method of producing an angular

body, consisting in machining a bar of irregular configuration in cross section to smaller dimensions at spaced intervals, drilling an opening axially in one end of the bar, severing the machined and drilled portions 70 from the main body of the bar, and subsequently drilling an opening in the severed product at an intersecting angle to the first opening.

16. A method of producing an angular 75 body, which includes the steps of forming a reduced cylindrical portion off center in and lengthwise of a rod, and of severing from the main body of the rod a section thereof adjacent to and including said cylindrical portion.

17. A method of producing an angular 80 body, which includes the steps of forming reduced cylindrical portions at spaced intervals lengthwise of a rod and offset to the 85 main axis of the rod, and of severing the section so formed from the main body of the rod.

18. A method of producing an angular 90 body from rabbeted rod or bar, which includes the step of forming cylindrical portions at spaced intervals in the main body of the bar, and of producing an enlarged extension at right angles to the axis of said bar intermediate said cylindrical portions.

In testimony whereof I affix my signature. 95
